ELECTRICAL CONDUIT COUPLER

Walter H. Weber, Metuchen, N. J.

Application December 14, 1951, Serial No. 17,738

Term of patent 14 years

(Cl. D26—1)

To all whom it may concern:

Be it known that I, Walter H. Weber, a citizen of the United States of America and a resident of Metuchen, county of Middlesex, and State of New Jersey, have invented a new, original, and ornamental Design for an Electrical Conduit Coupler, of which the following is a specification, reference being had to the accompanying drawings, forming a part thereof.

Fig. 1 is a side elevational view of the electrical conduit coupler showing my new design; and

Fig. 2 is an end view, both of which have the same appearance.

What is claimed is:

The ornamental design for an electrical conduit coupler, substantially as shown.

WALTER H. WEBER.
